CORD HOLDER

George Bouziane, Janesville, Wis.

Application March 5, 1940, Serial No. 322,392

1 Claim. (Cl. 242—141)

This invention relates to a cord or twine holder especially adapted for installation on counters and similar devices, and which will be out of the reach and sight of customers and the public and within convenient reach of the clerk or bundle wrapper.

The primary object of this invention is the provision of an efficient and inexpensive device of the above stated character which will be extremely easy to install on a display case or counter and will so support the ball of cord or twine that the cord or twine can be easily obtained in amount or lengths as desired and will be out of the way free from handling by customers or the public and consequently permits the cord or twine to be kept in a sanitary condition and thereby eliminate waste.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a fragmentary side elevation, partly in section, illustrating a cord holder mounted on a display case and constructed in accordance with my invention.

Figure 2 is a fragmentary top plan view illustrating a portion of the counter of the display case and an opening provided in the counter to permit passing of the cord therethrough.

Figure 3 is a perspective view illustrating the cord supporting bracket.

Figure 4 is a fragmentary vertical sectional view illustrating the cord mounting carried by the bracket.

Figure 5 is a perspective view illustrating the cord guide.

Figure 6 is a sectional view taken on the line 6—6 of Figure 5.

Referring in detail to the drawings, the numeral 5 indicates a display counter or cabinet on which the counter 6 is arranged at the rear side thereof and on which the store clerk may wrap goods or articles. The counter 6 is provided with an opening 7 to permit wrapping cord or twine to be passed therethrough. The foregoing description briefly sets forth a display case or cabinet and its counter to which the present invention is adapted for the purpose of supplying to the clerk in a convenient manner cord or wrapping twine as needed in the operation of wrapping articles or goods.

A substantially U-shaped bracket 8 is mounted on the rear wall of the display case or cabinet 5 below the counter 6 and includes parallel arm portions 9 and a connecting portion 10. The free end of one of the arm portions has a slight curvature thereto, as shown at 11, and also has therein a cord guide opening 12. The other arm portion 9 of the bracket has an opening 13 to receive a fastener 14 in the form of a screw for the purpose of detachably securing on the latter- 5 named arm portion a cone-shaped member 15 employed for the support of a ball of twine or cord indicated by the character 16. The cord or twine leaving the ball 16 is passed through the guide opening 12 and the opening 7 in the 15 counter 6.

A guide plate 17 of substantially triangular shape has an angularly related flange 18 notched to receive fasteners 19 for securing the guide plate on the cabinet 5 above the counter with 20 the major portion of the guide plate extending at right angles to the rear face of the cabinet. The notches in the flange 18 are indicated by the character 20 and the guide plate substantially intermediate its ends is provided with a slot 21 25 through which the cord or twine is passed after passing through the opening 7 of the counter 6. The apex portion of the plate 17 is slightly curved and is provided with a guide opening 22 through which the cord extends after passing through the slot 21. The cord on leaving the opening 22 depends downwardly within convenient reach of a person standing behind or adjacent to the counter 6 so that the cord can be easily obtained for 30 wrapping articles or the like.

From the foregoing description when taken in connection with the drawings it will be seen that the present invention may be easily installed and will efficiently support a ball of cord and feed the cord from the ball to the user in a very efficient and convenient manner still maintaining the cord out of reach of the public or customers. Furthermore, it will be seen that the ball of cord can be easily placed on its support and removed 40 therefrom when desired. By having the ball of cord located below the counter makes it more accessible for renewal by the clerk than if supported at a high elevation within the store.

It is believed that the foregoing description, 50 when taken in connection with the drawings, will fully set forth the construction and advantages of this invention to those skilled in the art to which such a device relates, so that further detailed description will not be required.

Having thus described my invention, what I claim is:

In combination with a store showcase having a horizontally disposed counter mounted on the rear wall thereof and provided with a string opening located adjacent the showcase, a substantially U-shaped bracket including spaced arms and a connecting portion arranged vertically to position the arms one above the other and secured 10 on the rear wall of the showcase below the counter placing the uppermost arm in close proximity to the under face of the counter, said

latter-named arm having a string opening to receive string as it leaves a ball of string mounted on the other arm, said string passing through the opening of the counter, and a substantially triangular shaped plate secured on the rear wall of the showcase and extending upwardly and outwardly therefrom above the counter and provided with spaced openings adapted to have the string passed therethrough and depend downwardly for reach by a person working behind the counter. 5

GEORGE BOUZIANE.
